UNITED STATES PATENT OFFICE.

WILLIAM M. SCHLESINGER, OF PHILADELPHIA, PENNSYLVANIA.

ELECTRIC-RAILWAY CAR-BRAKE.

SPECIFICATION forming part of Letters Patent No. 378,980, dated March 6, 1888.

Application filed August 26, 1887. Serial No. 247,976. (No model.)

To all whom it may concern:

Be it known that I, WILLIAM M. SCHLESINGER, a subject of the Queen of Great Britain, residing at Philadelphia, in the county of 5 Philadelphia and State of Pennsylvania, have invented certain new and useful Improvements in Electric-Railway Car-Brakes, of which the following is a specification.

My invention has relation to electrical braking appliances for that system of electrical railways having an electrically-propelled car which is in circuit by way of a current-collector traveling with the car in contact with line-conductors located adjacent to the line of 15 the track-rails.

Heretofore the electrical brakes for the cars in the above-described system of electrical railways have been operated either by the armature-current alone or by the line-current 20 alone. By the "armature-current" is meant the current which is generated in it or in the motor after it is cut out of the line-circuit preparatory to applying the brakes, which current is generated by the momentum of the car 25 revolving the armature of the motor and momentarily converting it into a generator between the interval of applying the brakes and the time at which the car comes to a state of rest. By the "line-current" is meant the current fed to the line-conductors from a generator located at a station or stations along the line of way and which is conducted to the motors on the car by the current-collectors attached to and traveling with the cars. The 30 use of either the armature or the line-current alone for operating the brake appliances, as heretofore done, is accompanied by respective advantages and disadvantages which in some respects are so nearly balanced 35 that there is practically no decided advantage in using one or the other separately, except as hereinafter particularly noted. Thus in the use of the armature-current alone the following advantages are gained: First, no external 40 energy—*i.e.*, the line current—is spent or used in stopping the car; second, the car is not only stopped by the brake appliances, but also indirectly by the consumption of energy 45 of the motor when acting as a generator for the time being; third, the slowing down of the speed of the car, due to these two reasons, is therefore very rapid; but these advantages

are overbalanced by the disadvantage that after the car slows up the motor does not generate sufficient current to bring the car quickly 55 to a full stop, especially if it is upon a grade—that is to say, from a high speed the car slows up quickly, but from a slow to a still slower speed for fully stopping the car the slowing-up is so very gradual that the use of the armature-current for operating the brake appliances has heretofore been deemed impracticable, as its action is too slow upon a level and does not stop the cars upon a grade. The use 60 of the line-current alone, either for slowing down the speed of the car or for bringing it to a full stop, has the disadvantage that it requires a large expenditure of outside energy or of the line-current; but in using it the brakes can be put on or applied as quickly as power 65 is calculated for doing so, and can be kept on as long as desired to hold the car upon a grade as well as upon a level. It is for this last-described advantage that the use of line or supply currents for operating the electrical 70 brake appliances of a car is most commonly employed or deemed the best available for the purpose.

It is obvious that if the electrically-actuating brake appliances of a car could be operated at will either by the armature-current or by the line-current, the former being used for quickly slowing up the speed of the car when this only is to be done without coming to a full stop, and for doing so preparatory to 85 successively using the line-current to bring the car to a full stop when needful, an economical and effective electrically-actuated system of car-braking would be secured which would combine the advantages derived from using 90 either the armature or the line currents singly, without being subject to either of their disadvantages.

To accomplish this described result is the object of my invention; and it consists, first, 95 of a railway-car having electrically-actuated brake appliances, an electric motor, a supply-circuit therefor, a switch and circuit-connections for cutting the electric motor out of and putting it in the line or supply circuit, and 100 another switch and circuit-connections for first placing the armature of the motor in circuit with the brake appliances and the latter successively in circuit with the line or supply

circuit for the motor; and, second, to the combination, construction, and arrangement of parts, as hereinafter more particularly described and claimed.

5 The accompanying drawing is a diagram, partly in perspective, of part of the running-gear of a car and its brake appliances, part of the electric motor or its armature therefor, contact-plow or current-collector, and part of 10 the line-conductors, switches, and circuit-connections, including resistances therein for regulating the consumption of power, embodying my invention.

A represents a pair of wheels for the running-gear of a car; B, the brake-shoes therefor, having lever or other connections, b, with the armature or core of an electro-magnet or solenoid, C, for operating said shoes; D, the armature for the electric motor for the car, the 20 shaft of which is suitably geared to one of the axles of the running-gear of the car in the usual or other desired way; E, the current-collector, in contact with a portion of a line of conductors, F F; and G, a switch for cutting 25 the car-motor or its armature D out of and placing it in the line-circuit F F, or in a loop or branch therefrom, all of which may be constructed and arranged for operation relatively to one another upon the car in the usual manner or otherwise, as desired.

H represents another switch or regulator, composed of a pivoted lever, h, having at one end a contact-bridge, h', and at its opposite end two contact-bridges, h² and h³, all of which 35 are suitably insulated from one another, as desired.

Circumferentially arranged in relation to the center or pivot-point of lever h, and in line with its contact-bridge h', are two series of 40 segmental plates or contacts, h⁴ and h⁵ and h⁶ and h⁷, the plates h⁴ and h⁶ being single plates, and the plates h⁵ and h⁷ consisting of a number or series of plates, as shown.

Between the plates h⁵, in any suitable manner, are preferably located suitable resistances, i, which resistances place said plates in circuit series with one another, and from each of the plates h⁷ leads a wire or connection, 1, to the respectively-located plate of the series of 50 plates h⁵ to put any one of the plates h⁷ in series with the plates h⁵ and resistances i. Consequently no separate or additional resistances need be inserted in the circuit-connections for plates h⁷. From the last or one of the end 55 plates of the series of plates h⁵ leads a wire, 2, to one side of the solenoid or magnet C.

h⁸ and h⁹ and h¹⁰ and h¹¹ represent other pairs of segmental contact-plates correspondingly located about the center or pivot-point of the 60 lever h, in line, respectively, with the contact-plates h² and h³ on said lever. The plates h⁸, h⁹, h¹⁰, and h¹¹ are single plates, as shown. Plates h⁸ and h¹⁰ are in circuit with wire 3, leading to the other side of the magnet or solenoid 65 C. From plate h⁹ a wire, 4, leads to a binding-post, l, and from plate h¹¹ a wire, 5, leads to a separate binding-post, l'. Plate h⁶ is con-

nected by a wire, 6, to another binding-post, l', and plate h⁴ by wire 7 to a separate binding-post, l'. 70

From binding-posts l' and l', respectively, lead wires 8 and 9 to the current-collector wires e and e', and from binding-posts l and l', respectively, lead wires 10 and 11 to current-collector wires e and e', or they may connect 75 with the wires 8 and 9, as shown. These wires 10 and 11 respectively include the fixed contact-plates g and g', suitably insulated, of the switch G. The circuit of the wires 10 and 11 is suitably closed or opened through switch 80 G by pushing the movable contacts g² and g³ into or out of contact with the plates g' and g, respectively, in any suitable manner, either manually or otherwise. The lever h of regulator H is preferably provided with a retracting-spring, h¹², and a stop, h¹³, whereby said spring normally acts to pull the lever over against the stop h¹³ and normally open the circuit-connections through the regulator, as shown in the drawing. 90

The operation is as follows: To propel the car or place its motor in a branch or loop circuit with the line-conductors F F by way of the current-collector E, the movable contacts g² g³ of the switch G are pushed or placed in 95 contact with the switch-plates g' and g, respectively. This movement closes the circuit of the wires 10 and 11 to binding-posts l' and l, and thence by way of wires 12 and 13, respectively, from said binding-posts to the 100 brushes d for armature D or the motor. The line-current must then necessarily pass to the motor or armature D by way of wires 12 and 13, as described, because the connections 7 and 4, leading from binding-posts l' and l to the 105 regulator H, are then open. To apply the brakes B at any time while the car is in motion, the movable contacts g² g³ are first pushed out of contact with the plates g' g to open switch G, as shown in the drawing, and cut 110 the motor or armature D out of the line-circuit, whereupon the momentum of the car converts the motor into a generator. The lever h is then moved in the direction indicated by arrow x in the drawing to cause its plate h' 115 to bridge the contacts h⁴ and h⁵ and its plate h² to bridge the contacts h⁸ and h⁹, whereupon the circuit of wires 12 and 13, including armature D, is completed by way of binding-posts l' l, wires 7 and 4, plates h⁴ h⁵ h⁶ and h⁸ h⁹ and h¹⁰, and wires 2 and 3, respectively, through 120 solenoid or magnet C, which is then energized by the armature-current to apply the brakes and quickly slow the speed of the car from a high to a low speed. As the plate h' of lever 125 h passes over the successive plates h⁶, the resistances i are successively cut out of the armature-circuit as the strength or intensity of its current diminishes by reason of the slowing down of the speed of the car, and when the 130 plate h' contacts with the end plate, h⁵, to the right of the series of said plates in the drawing all of the resistances i are cut out of the armature-circuit, at which point the strength

of the armature current is weakest. This armature-current then may alone be used for slowing down the speed of the car; but if it is insufficient to actuate the brakes to stop the car the movement of lever h is continued in the direction above described until its plate h' bridges the contacts $h^6 h^7$ and its plate h^8 bridges the contacts h^{10} and h^{11} , whereupon the armature D is cut out of the circuit of magnet or solenoid C, and it is included in or is in a loop or branch from the line-conductors, which loop comprises wire 2, one of the wires 1, resistances i , one of the plates h^7 , plates h^8 and h^6 , wire 6, binding-post l^7 , wire 9, current-collector E, wire 8, binding-post l^8 , wire 5, plates h^{11} h^3 h^{10} , and wire 3, whereupon the line-current from the conductors F F energizes the solenoid C to quickly slow down the speed of the car from a slow to a still slower speed until it is brought to a state of rest, and is maintained in such a position, whether upon a level or upon a grade, so long as the line-current is utilized for applying the brakes, as above described. To relieve the brakes the lever h of regulator H is let go of, whereupon its spring h^{12} reacts to return it to its normal position and cut the solenoid C out of the branch from the line-conductors. The switch G is then operated to place the motor or armature D in circuit with the current-collector E, as first above described, to again start and propel the car. The resistances i serve, it will be noted, both for the armature and the line currents; hence the consumption of power is regulated as desired by moving the lever contact-plate h' to successive plates $h^7 h^8$ of the series of the same in the well-known manner used for adjustable resistances, and the solenoid C is at all times protected.

I have shown and described my improvements in connection with an electrically-propelled car the motor of which is supplied by a line-current; but it is obvious that they are equally applicable to a car having a battery or generator located upon it for supplying a current to the motor.

It is also obvious that the construction and the arrangement of the detail parts of the appliances comprising my invention may be greatly varied without departing from the spirit of the same, and hence I do not limit myself to the construction and arrangement shown. Thus, for instance, many different forms of switches G, either simple make-and-break switches, as shown, or the usual or any form of reversing and make-and-break switches, may be used, and modified constructions of regulators H may be substituted for the form shown; or the switch G and the regulator may be combined in any of the well-known ways, as I have herein shown them separately for the sake of clearness in defining my improvements.

From the foregoing it will be noted that the circuit-connections 2 3 for the magnet or solenoid C are preferably normally open and lead to switch H; that the outside armature-circuit

10 13 and 12 11, which includes switch G, leads to the supply or line circuit, or is a loop or branch therefrom, and said armature-circuit 70 has a branch, 4 7, which is normally open and leads to switch H, and that the supply or line circuit has a branch or loop, 5 8 6 9, preferably normally open and also leading to switch H; hence by suitably manipulating switch G 75 the armature or motor is cut out of or placed in the line-circuit, or in a loop therefrom, without changing the normal condition of the remaining circuits, and when cut out, as above described, and by suitably moving the lever h 80 of switch H, the circuit of the solenoid C may be closed through or shifted to the outside circuit 7 12 4 13 of the armature D alone, or successively to it and to the line-circuit or its loop or branch 5 8 6 9, whereby said solenoid may 85 be energized only by the armature-current when the motor is acting as a generator, or successively by the armature-current and by the line or supply current.

The field-magnets $d' d'$ for the armature D 90 may be included in a branch from wires 10 and 11, or otherwise, as desired.

I do not herein claim the method for operating or applying electrically controlled or actuating brakes on an electrically-propelled 95 car, consisting of first cutting the car-motor out of the generator or supply-current circuit to convert said motor into a generator driven by the momentum of the car and then successively using the armature-current of the 100 motor and the supply-current to successively actuate said brake appliances, nor to accomplishing such described result by successively using separate electric currents—one of a gradually-decreasing intensity and volume and the 105 other of a constant intensity and volume—as I reserve the same for the subject-matter of a method application for United States Letters Patent for same.

What I claim is—

1. The combination of a car or vehicle, an electric motor for propelling the car, a supply-circuit for the motor, electrically-actuated brake appliances for the car, and electric regulating devices and circuit-connections for successively cutting the motor out of its supply-circuit, for including the brake appliances in the circuit of the motor-armature, and for including the brake appliances in the supply-circuit for the motor, substantially as set forth. 115 120 125

2. The combination of a car or vehicle, an electric motor for propelling the car, a supply-circuit for the motor, electrically-actuated brake appliances for the car, and electric regulating devices and circuit-connections having 125 adjustable resistances and arranged for operation to successively cut the motor out of its supply-circuit, for including the brake appliances in the circuit of the motor-armature, and for including the brake appliances in the 130 supply-circuit for the motor, substantially as set forth.

3. The combination of a car or vehicle, an electric motor propelling the car, a line-circuit,

a traveling current-collector on the car in contact with the line-circuit, electrically-actuated brake appliances for the car, and electric regulating devices for cutting out the motor from the line-circuit and for successively including the brake appliances in the armature-circuit of the motor and in the line-circuit or a loop therefrom, substantially as set forth. 4. The combination of a car or vehicle, an electric motor, electrically-actuated brakes, a supply-circuit for said motor, a regulator, H, comprising contact-plates $h^4 h^5$, $h^6 h^7$, $h^8 h^9$, and $h^{10} h^{11}$, pivoted lever h , having insulated bridges h' , h^2 , and h^3 , and circuit-connections between said plates and the brake appliances, the motor-armature, and the supply-circuit, substantially as set forth. 5. The combination of a car or vehicle, an electric motor, electrically-actuated brakes, a supply-circuit for said motor, and a regulator, H, comprising contact-plates $h^4 h^5$, $h^6 h^7$, $h^8 h^9$, and $h^{10} h^{11}$, pivoted lever h , having insulated bridges $h' h^2 h^3$, and circuit-connections, including resistances i , between said plates and the brake appliances, the motor-armature, and supply-circuit, substantially as set forth. 6. The combination, with a car having an electric motor, supply-circuit for the motor, and electrically-actuated brakes, of electric regu-

lator and circuit-connections for cutting the motor out of its supply-circuit, for including the brake appliances in the circuit of the motor-armature, and for including said brake appliances in a loop or branch from said supply-circuit for quickly slowing the speed of the car first by the armature-circuit of its motor, and for successively and quickly slowing down the speed of the car from a slow to a still slower speed until it stops by the supply or line current, substantially as set forth. 40

7. The combination of a magnet or solenoid, C, switch H, circuit-connections between said switch and magnet, an electric motor, a line or supply circuit including a cut-out switch for the motor, and circuit-connections between the line or supply circuit and switch H, and between the latter and the armature of the motor, whereby a movement of switch-lever of switch H places the solenoid C successively in the armature-circuit and in the line circuit, substantially as set forth. 50

In testimony whereof I affix my signature in the presence of two witnesses.
